 a corporation of New York

Application March 12, 1948, Serial No. 14,456

7 Claims. (Cl. 178—69.5)

1

This invention relates to telefacsimile apparatus and more particularly to the motor drive and phasing mechanism employed for starting and driving the drum or other scanning member in controlled speed and phase relation.

One object of the invention is to provide an improved and efficient facsimile drive which is adapted to start a relatively large picture drum or scanning member from rest, bring it into proper phase relationship and rotating at a desired constant speed in synchronism with the machine with which it is connected.

Another object of the invention is to provide an improved phasing mechanism for facsimile or telephoto apparatus in which the phasing load on the motor is low.

Another object of the invention is to reduce the power required to drive the scanning mechanism of a facsimile machine to a minimum.

A further object of the invention is to provide an improved drive arrangement for the picture or recording drum of apparatus of the character described employing a driving motor of a non-synchronous type and a second motor of a synchronous type so interconnected that the driven element rotates at a speed determined by the synchronous motor.

A still further object of the invention is to provide an improved drive arrangement for apparatus of the class described which is adapted to bring the driven element up to synchronous speed and effect a phasing operation automatically in response to the closure of control switches without requiring manipulative skill to start and phase the facsimile equipment.

Still another object of the invention is to provide driving mechanism for the drum of a facsimile machine which will permit the drum to be stopped or held stationary during or after the phasing operation without losing phasing adjustment.

Other objects and advantages of the invention will appear from the following detailed description of the embodiment thereof shown in the accompanying drawings, wherein

Fig. 1 is a perspective view, partly in section, of a preferred construction. In this view the element to be phased in its angular position and driven at constant speed is shown as a drum or cylinder of a facsimile machine.

Fig. 2 is a perspective view showing the relation of the driving and phasing elements of Fig. 1 in a simplified and exploded form in order to show more clearly the underlying principles of construction.

2

In telefacsimile apparatus in general use, picture transmitting and recording drums are employed which are driven at a constant speed and in a desired phase relation. In this manner the drums of the transmitter and recorder are operated in rotational synchronism and in phase. In some apparatus other types of scanning devices are employed instead of the drums, which are also required to be operated in controlled speed and phase relation.

In order to maintain the drum or scanning member of the recorder operating at the same speed as that of the transmitter, the respective scanning members may be driven by synchronous motors, each controlled by a tuning fork or other frequency standard or connected to the same alternating-current system. Another synchronizing arrangement involves transmission of a low-frequency carrier from the transmitting station to the receiving station and synchronizing the speeds of the two motors by the carrier. In most synchronizing systems, the synchronous motor is driven by a vacuum tube amplifier. Consequently it is desirable to reduce the size of the synchronous motor element as much as possible by reducing the load imposed thereon by the drum or scanning member. However, if the drum is started and stopped for phasing, usually a friction clutch is provided and considerably more power is required to prevent stalling the synchronous motor by the clutch load than for merely maintaining the operating speed of the drum. At the present time, facsimile equipment is being used which employs relatively large picture drums or rotating members driven at relatively high speeds and therefore requiring increased driving power.

It has been found impractical to connect these high speed scanning members directly through a friction clutch to the synchronous motor because a large clutch is required to pick up the drum load without slippage and this in turn requires a motor of unreasonable size and a large power source for the motor. It has been proposed to reduce the clutch friction load by maintaining the drum or scanning member rotating through a secondary clutch or other auxiliary drive means but the construction is rather complicated, particularly as it was necessary to insure that the auxiliary clutch would not drive the drum at a speed greater than synchronous speed or provide in some manner for bringing the drum to synchronous speed.

In accordance with the embodiment of the invention illustrated, the synchronous motor is con-

nected to a rotatable phasing member and a driving connection in the form of a latch is provided between the phasing member and the drum so that the drum is coupled to the phasing member in one predetermined angular position of the drum relative to said member. Further means is provided for overdriving the drum so that when the phasing member has been released or phased and is rotating at synchronous speed, the drum will catch up to the phasing member and rotate at the synchronous speed of said member with the driving load taken by the motor employed for overdriving the drum. The driving connection between the rotatable phasing member and the synchronous motor or other constant-speed control member enables the phasing member to be stopped for phasing without stalling the synchronous motor. This driving connection is preferably of a type which positively controls the speed of the phasing member without imposing more than a minimum load on the synchronous motor. A variable speed motor may be employed for overdriving the drum or the synchronous motor may be geared through a direct drive shaft to the drum with an interposed friction slip clutch. In accordance with a further feature of the invention, the synchronous motor is preferably connected to the phasing member through a worm and worm gear of a type which prevents torque from the phasing member overdriving the synchronous motor above synchronous speed, such as an irreversible worm-gear drive or a worm-gear drive designed to limit the torque applied to the synchronous motor shaft.

Referring to the drawing, the drum 1 of a facsimile machine is mounted on a shaft 2 for rotation at a constant speed during transmission. The drum 1 may be a picture drum of a facsimile transmitter, in case the transmitter is phased with a remote recorder, or may be the recording drum of a recording facsimile machine where such recorder is phased with a remote transmitter. It is further understood that the drum 1 is intended to represent any rotatable scanning element of this character which is to be controlled in speed and phase relation. The shaft 2 is shown as provided at the outer end thereof with a drive gear 3 meshing with a drive pinion 4 for the purpose of starting the drum 1 from rest and bringing it up to a desired rotative speed. A shaded-pole motor or other variable speed motor may be provided for overdriving the drum through the gears 3 and 4, or other suitable driving means may be provided for initially accelerating the drum 1 and providing all or a part of the torque required for the driving load. An induction motor having a high slip-speed characteristic may be used as a drive motor since it has a fairly constant torque over a considerable range of speed.

In order to control the speed and phase relation of the drum or scanning member 1, a rotatable phasing member 6 having a projecting lug 7 is provided in the specific embodiment shown by way of illustration. The phasing member 6 is coaxial with the drum or scanning member 1, and may be journaled on the shaft 2. The position of the phasing member may be controlled by a timed phasing current impulse, as shown for example in my prior patent, No. 2,275,249 granted Mar. 3, 1942. In order to stop the phasing member 6 in a predetermined phase relation (predetermined angular position) and release the same in response to the receipt of a phasing pulse, means such as a pivoted latch member 8 controlled by

an electromagnet 9 may be provided. As shown, the latch member 8 is disposed in the path of the lug 7 and stops the rotation of the phasing member 6 until the latch is retracted by energization of the magnet 9 upon receipt of a phasing current pulse applied to the conductors 10.

The phasing member 6 is driven at a constant synchronous speed by means described herein-after and serves to control the speed of the drum 1 by means of a phasing coupling means 12. In the embodiment shown, the coupling means 12 is in the form of a latch operative to couple the scanning means 1 and phasing member 6 together in one relative angular position of the two members. It preferably consists of a two-way double-jointed latch pivoted on the scanning member and adapted to engage the lug 7 of the phasing member 6. As shown, the coupling means 12 comprises a fixed base or supporting element 13 rotating with the drum, a first pivoted latch member 14 and a second latch member 15 pivoted on the member 14. The latches 14 and 15 are arranged to pivot in opposite directions, as indicated by the arrows in Fig. 1. A strong spring 16 is interposed between the members 13 and 14 so that the latch can tilt by the pivoting of the member 14 only in response to the application of considerable force. On the other hand a light spring 17 is interposed between the members 14 and 15 so that the member 15 can tilt to permit the lug 7 of the phasing member 6 to pass the latch in a clockwise direction without imposing substantial drag on the phasing member. Thus the phasing member 6, if driven at constant speed, will serve to hold the drum 1 at the same speed, through the coupling connection 12 when the drum is overdriven by the shaft 2. When the shaft tends to run above synchronous speed, the connection 12 engages the lug 7, the spring 16 being sufficiently strong to prevent buckling of the latch 13, 14 by the driving torque. However, if excessive torque is applied between the drum 1 and the phasing member 6, either while the drum is rotating or as a result of turning it by hand 45 when the phasing member 6 is stopped by the latch 8, the pivoting of the member 14 of the latch will prevent damage to the coupling 12.

The rotative speed of the phasing member 6 is maintained at the constant synchronous speed by means of a motor 21; or in case a fluctuating scanning speed is used, as explained for example in my prior Patent No. 2,404,566, the motor 21 maintains synchronism of the member 6. The motor 21 is preferably a synchronous motor which is synchronized with the driving motor of the remote facsimile machine, as by means of a transmitted carrier or by the use of common or synchronized sources of alternating current for driving the motors, as well known to those skilled in the art. As shown, the motor 21 is connected to the phasing member 6 through a worm 22 and worm gear 23, the latter being connected to a driving sleeve 24 surrounding the shaft 2. The worm gear 23 is shown as clamped to the sleeve 24 by a clamp 25. The sleeve 24 in turn is keyed to a ratchet gear 26, the teeth of which are engaged by a pivoted pawl 27 on the phasing member 6. The pawl 27 is pivoted on a stud 28 and is urged by a spring 29 against the circumference of the toothed ratchet gear 26. The pawl and ratchet connection shown is provided for the purpose of permitting substantially free rotation of the synchronous motor rotor when the phasing member 6 is stopped without imparting a heavy frictional drag on the synchro-

uous motor, while at the same time the phasing member 6 is positively held back (to synchronous speed) by the synchronous motor 21 when released for rotation upon the receipt of the phasing pulse controlling the latch 8.

When the phasing member 6 is stopped by the latch 8, the motor 21 drives the ratchet gear 26 in a clockwise direction, the pawl 27 slipping over the teeth in the gear. When the phasing member 6 is released for rotation, however, since the friction load is small the pressure of the pawl on a tooth of the gear 26 is sufficiently great to effect a rather positive drive between the said gear and the phasing member 6 on which the pawl is pivoted. In this manner the phasing member is operated at the synchronous speed of the drive shaft substantially instantaneously after the phasing pulse is received. The driving power of the pawl and ratchet in this direction is determined by the shape of the pawl and ratchet teeth and the pressure of the spring 29, and thus is not a variable factor like the friction drive of the slip clutch heretofore used. In the opposite direction, when the overdrive tends to rotate the drum and phasing member 6 above synchronous speed, the pawl and ratchet teeth are shaped to provide positive torque transmission so that the motor 21 positively limits or retards the phasing member to the desired synchronous speed.

The general principles underlying the invention will be readily understood from the simplified drawing of Fig. 2, which illustrates the essential relation between the driving, phasing and scanning members of Fig. 1 in a simplified form. As shown, referring to Fig. 2 and using corresponding reference characters to denote corresponding elements of the construction, the drum 1 is driven through the shaft 2 by "over-drive" means operative to bring it up from rest to the desired speed and tending to rotate the drum above synchronous speed. Obviously, instead of a separate induction or other variable speed motor, the shaft 2 may be driven from the synchronous motor 21 through a slip-friction clutch. The drum 1 is maintained at constant speed by the retarding force applied through the coupling means 12 and the lug 7 of the phasing member 6 which is driven at constant or synchronized speed by the synchronous motor 21. Thus, when the drum 1 catches up to the phasing member 6 and the coupling means 12 engages the lug 7, the drum is retarded and constrained to operate at the synchronous or controlled speed of the phasing member 6. The driving connection consisting of the pawl and ratchet 26, 27 permits the continued operation of the synchronous motor 21, when the phasing member 6 is latched during the phasing operation. This is required because the drive for the phasing member must be operating at synchronous speed at the instant the phasing member is released by the phasing pulse. However, the pawl and ratchet provide a drive connection which has a minimum frictional drag when the phasing member 6 is stopped, and which picks up the phasing member with negligible slippage when it is released.

In accordance with another feature of the invention, the worm-gear drive 22, 23 is designed to not only avoid undue loading of the synchronous motor 21 by the drum drive but also limit the reverse torque on the motor tending to pull it out of synchronism. The friction between a worm and worm gear depends upon load and

speed as well as the material and profiles of the worm threads and gear teeth. However, for average conditions in apparatus of the character described, the helix angle of the thread (the angle of thread with a line at right angles to the axis of the worm) should be of the order of 7 to 12 degrees. As noted, this angle for optimum results will change for different materials, speeds, and so forth but improvement will be obtained generally in the stated range for ordinary gear materials. In this manner, the size of the synchronous motor 21 may be reduced to a minimum since the stalling and accelerating torques produced by the overdrive are small. In starting and phasing the drum or scanning member 1, the circuit of the synchronous motor 21 is closed and the motor brought to synchronous speed. If the phasing member 6 is locked by the phasing latch 7, the ratchet mechanism 26, 27 permits the synchronous motor 21 to operate at synchronous speed without appreciable drag because of the locking of the phasing member 6. When the phasing pulse is received, the latch member 8 is retracted from the phasing lug 7, and the phasing member 6 rotates with the ratchet gear 26 at synchronous speed. The drum is brought up to speed by closing its motor circuit, either before or after phasing, and tends to rotate above synchronous speed. When the drum 1 catches up to the phasing member 6, and the coupling means 12 engages the lug 7 of said member, the drum 1 is retarded by the phasing member 6 and continues to rotate in the desired phase relation and at synchronous speed.

It will be apparent that the invention provides an effective phasing mechanism in which a large high-speed scanning member can be brought to the desired phase relation with a phasing member controlled by the phasing pulse, and maintained at desired synchronous speed by means of a small synchronous motor. Since the load on the synchronous motor is small, even when the phasing member is stopped for phasing, there is no possibility of stalling the motor. On the other hand, the relatively heavy power required to start and rotate the drum or scanning member 1 is obtained from an auxiliary power source which need not be closely regulated as to speed, such as a variable-speed shaded-pole motor.

It will also be noted that in case of a variable scanning speed of transmitter and recorder, as employed in the secrecy or scrambler equipment disclosed in my above-mentioned Patent No. 2,404,566, the motor 21 when synchronized with the driving mechanism of the remote machine is adapted to control the rotation of the drum 1 in accordance with variations in the rotative speed of the motor. The driving mechanism according to the invention has the advantage that rapid, wide-range variations in the speed of the scanning means may be controlled by a small motor 21 of the synchronous type. The term "synchronous speed" is to be construed as including a variable speed which is synchronized with the fluctuations in speed of a second scanner or scanning drive motor.

A further advantage of the mechanism described above resides in the fact that the drum 1 is movable with respect to the scanning member 6 except when actually transmitting or recording and the drum may be actually stopped during or even after the phasing operation without requiring re-phasing of the member 6.

While I have described in detail a preferred

embodiment of the invention for the purpose of explaining the underlying principles thereof, such description is only by way of illustration. Various modifications of the invention will occur to those skilled in the art, and may be made without departing from the scope thereof.

I claim:

1. In a telefacsimile machine provided with a rotatable scanning member to be driven at predetermined speed and phase relation, in combination, motor means in direct driving relation to said scanning member tending to drive the scanning member above synchronous speed, a rotatable phasing member, means including said phasing member for controlling the angular position of the scanning member in operation, means for supporting said phasing member for rotation independent of said scanning member, means for stopping the phasing member and for releasing the same for rotation when a phasing pulse is received, a second motor means operating at synchronous speed and connected to the rotatable phasing member to maintain the rotative speed of the scanning member at synchronous speed and a drive connection between said second synchronous motor means and said phasing member embodying a pawl and a ratchet gear engaged thereby to allow rotation of the motor shaft when the phasing member is stopped for phasing control, the teeth of said pawl and gear being shaped to provide a positive light driving torque from said synchronous motor means on the phasing member when it is released.
2. In a telefacsimile machine provided with a rotatable scanning member to be driven at predetermined speed and phase relation, in combination, a motor which varies in speed in accordance with its load connected to and normally tending to drive said scanning member at a speed greater than the predetermined speed, a rotatable phasing member connected to said scanning member in such manner as to retard its speed when the phasing member and the scanner member have a predetermined phase relationship, means for supporting the phasing member for rotation independent of said scanning member, means for stopping the phasing member and for releasing the same for rotation when a phasing pulse is received, thereby controlling the angular position of the scanning member when the over-drive of the said member causes it to assume said predetermined phase relation to said phasing member, and means for continuously maintaining the rotative speed of said phasing member at said predetermined speed during operation and thereby limiting the rotation of the scanning member to such speed.
3. A facsimile driving and phasing mechanism according to claim 2 in which the means for maintaining the rotative speed of said phasing member at said predetermined speed comprises a synchronous motor geared to the phasing member through an irreversible worm drive for limiting the loading of said synchronous motor by the over-drive of the variable-speed motor.

4. In a telefacsimile machine of the character described, in combination, a rotatable scanning member tending to rotate above synchronous speed, a rotatable phasing member connected to said scanning member in such manner as to retard its speed when the scanning member and phasing member have a predetermined phase relationship, means for supporting said phasing member for rotation independent of the scanning member, means for stopping the phasing member and for releasing the same for rotation when a phasing pulse is received, thereby controlling the angular position of the scanning member when in said predetermined phase relationship to said phasing member, and motor means for rotating the scanning member and for controlling the rotative speed of the phasing member to obtain a predetermined synchronous speed thereof and of said scanning member.
- 10 5. In a telefacsimile machine provided with a rotatable drum or scanning member, in combination, a rotatable phasing member coaxial with said drum, means for supporting said phasing member for rotation independent of the drum or scanning member, means including a latch member for coupling the phasing member to said drum, means for stopping the phasing member and for releasing the same for rotation when a phasing pulse is received, means including a synchronous motor for maintaining the rotation of the phasing member at a controlled or synchronous speed and thereby controlling the speed of the drum when the same is coupled to the phasing member and a pawl-and-ratchet drive connection between the synchronous motor and said phasing member to permit the synchronous motor to run when the phasing member is stopped while retarding the phasing member to the speed of said motor when said member is released for rotation.
- 25 6. A driving mechanism for a facsimile machine according to claim 5 in which the drive connection consists of a pawl and ratchet gear having teeth shaped to provide a light positive driving torque from the synchronous motor to said phasing member and relatively heavy positive retarding torque when the speed of the phasing member tends to exceed synchronous speed.
- 30 45 7. A driving mechanism for a facsimile machine according to claim 5 in which the phasing member is connected to the synchronous motor through worm gearing in which the thread helix angle of the teeth on the driving worm of the motor is of the order of 7 to 12 degrees.
